UNITED STATES PATENT OFFICE.

JAMES S. GORTON, OF NEW YORK, N. Y., ASSIGNOR TO THE WILLCOX & GIBBS SEWING MACHINE COMPANY, OF SAME PLACE.

DESIGN FOR A FEED-BAR SHOE FOR SEWING-MACHINES.

SPECIFICATION forming part of Design No. 33,219, dated September 18, 1900.

Application filed August 3, 1900. Serial No. 25,840. Term of patent 14 years.

To all whom it may concern:

Be it known that I, JAMES S. GORTON, a citizen of the United States of America, and a resident of the city of New York, borough of Brooklyn, in the county of Kings, State of New York, have invented and produced a Design for a Feed-Bar Shoe for Sewing-Machines, of which the following is a specification.

My design for a sewing-machine feed-bar shoe is represented in the accompanying drawings, in which—

Figure 1 is a perspective view looking up at the under side. Fig. 2 is a plan view. Fig. 3 is an edge view, and Fig. 4 is an inverted plan view.

My design comprises a cylindrical sleeve A, with a flat table B over it as long as the sleeve, but wider, and this table has a narrow projecting finger B', forming a continuation of it at one corner. Underneath the table at

the diametrically-opposite corner from the finger B' there is a rectangular projection D, merging into the sleeve A, and a slit a, parallel with the axis of the sleeve, extends 25 through one side of the latter and through the projection D. There is shown a vertical hole x in this projection and a smaller hole x', coincident with it in the table.

The essential feature of my design comprises the sleeve A, table B, finger B', projection D, and slit a, arranged as shown.

I claim as my invention—

The design for a feed-bar shoe for sewing-machines herein shown and described.

In testimony whereof I have signed my name to this specification in the presence of two subscribing witnesses.

J. S. GORTON.
